Primary Examiner — Messina L Smith(74) *Attorney, Agent, or Firm* — Jeenam Park(57) **CLAIM**

The ornamental design for an oven, as shown and described.

DESCRIPTION

FIG. 1 is a front, right and top perspective view of an oven, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged view of a portion of the oven labeled 9 in FIG. 1.

The dot-dash broken lines depict the boundaries of the enlargements that form no part of the claimed design.

1 Claim, 9 Drawing Sheets(56)
